[57] ABSTRACT

An electronic metronome has a visual indicator consisting of a package in which a plurality of different light color LED chips are mounted close to each other. Down-beat and up-beat are indicated as different color emissions from a single spot.

3 Claims, 4 Drawing Figures

FIG. 2

FIG. 3

ELECTRONIC METRONOME

BACKGROUND OF THE INVENTION

This present invention relates to electronic metronomes and more particularly to a metronome having a visual rhythm-displaying device with colours.

Conventional visual tempo-displaying devices display tempos with a single colour of a lamp or other visual indicator, but does not display rhythms.

BRIEF SUMMARY OF THE INVENTION

The principal object of the present invention is to provide an electronic metronome having a visual rhythm-displaying device which is provided with a visual indicator including a pair of light emitting diodes spaced close to and having different light colour from each other, displaying down-beat and up-beat with different colours.

It is another object of this invention to provide a compact and handy electronic metronome with low cost and with long life and good reliability.

BRIEF DESCRIPTION OF THE DRAWINGS

FIG. 1 is a circuit diagram showing an electronic metronome according to the invention,

FIG. 2 is a timing graph representing wave forms in the metronome of FIG. 1,

FIG. 3 is a sectional view of the indicator used in the metronome of FIG. 1, and

FIG. 4 is a circuit diagram of a second electronic metronome according to the invention.

DETAILED DESCRIPTION OF THE PREFERRED EMBODIMENTS

Some preferred embodiments of this invention will now be described referring to the attached drawings.

FIG. 1 is a circuit diagram of an electronic metronome of the invention, in which reference numeral 1 designates a tempo-signal generating circuit which selectively generates pulse signals at a desired tempo A, such as 92 cycles per minute for "moderate."

Reference numeral 2 designates a down-beat signal generating circuit including a set of flip-flops F₁, F₂ and F₃, a pair of NAND gates G₁ and G₂, a monostable-multivibrator 3, an OR-gate G₃ and a selecting switch 4 for time or rhythm selection. Flips-flops F₁, F₂ and F₃ are connected to each other with Q output terminal of flip-flop F₁ connected to clock-input terminal CP of flip-flop F₂, and Q output terminal of flip-flop F₂ connected to clock-input terminal CP of flip-flop F₃. The tempo signals of tempo-signal generating circuit 1 are applied to clock-input terminal CP of flip-flop F₁ so that the tempo signals are divided into half-cycle signals, quarter-cycle signals and one-eighth cycle signals by flip-flops F₁, F₂ and F₃.

Monostable-multivibrator 3 normally has level "1" at the output B and is changed to have level "0" there when a fall-down signal is applied to the input I of the multivibrator 3, the level "0" forming a short-length negative pulse. The output negative pulse is applied to the reset terminals R of flip-flops F₁, F₂ and F₃ to reset all of them.

A NAND-gate G₁ has two inputs, one being connected to output Q of flip-flop F₁ and the other connected to output Q of flip-flop F₂. Another NAND-gate G₂ also has two inputs, one being connected to output Q of flip-flop F₂ and the other connected to output Q of

flip-flop F₃. A selecting switch 4 is provided with switch terminals ①, ②, ③, ④ and ⑥. Terminal ① is connected to the output of tempo-signal generating circuit 1 to transfer tempo signals A to input terminal I of monostable-multivibrator 3. Terminal ② is connected to output Q of flip-flop F₁, terminal ③ being connected to the output of NAND-gate G₁. Terminal ④ is connected to output Q of flip-flop F₃ to transfer Q signal to input terminal I, terminal ⑥ being connected to the output of NAND-gate G₂ to transfer the output signals of gate G₂.

To an OR-gate G₃ are fed outputs Q of flip-flops F₁, F₂ and F₃ and tempo signals A. Therefore, the output of OR-gate G₃ takes level "0" (K_n) only when all the outputs Q of the flip-flops and tempo signal A take level "0". This output K_n is used as a down-beat signal.

Thus, when switch 4 is connected with terminal ①, down-beat signal K_n coincides with tempo signal A. When switch 4 is connected with terminal ②, down-beat signal generating circuit 2 operates as a binary counter and a down-beat signal K_a of a negative pulse occurs at every two negative pulses of tempo signal A as shown in FIG. 2. When switch 4 is selected to be connected with ③, ④ or ⑥, down-beat signal generating circuit 2 operates in turn as a divided by three, four or six counter and a down-beat signal K_b, K_c or K_d occurs at every three, four or six negative pulses of tempo signal A as shown in FIG. 2.

Down-beat signal K_n is applied to an indicator driving circuit 5 which includes two transistors T₁ and T₂.

30 The emitters of both the transistors T₁ and T₂ are connected in common to the power source VC by way of a resistor 8, and the base of transistor T₁ receives tempo signals A, the base of transistor T₂ receiving down-beat signals K_n. Reference numeral 6 designates a visual indicator including a pair of light emitting diodes LED₁ and LED₂ which are, in a state of raw chips, mounted close to each other in a package, as is well shown in FIG. 3, and which have different light colour, such as LED₁ has green light and LED₂ has red light. So indicator 6 emits, for instance, green or red light from a single point.

LED₁ is connected between the collector of transistor T₁ by way of a diode D and ground, so that, when tempo signal A takes level 0 (lower level), transistor T₁ is made conductive and LED₁ emits light. On the contrary, LED₂ is connected between the collector of transistor T₂ and ground, so that, when down-beat signal K_n (level "0") is applied to the base of transistor T₂, transistor T₂ is made conductive and LED₂ emits light.

When inputs of level "0" are applied to the bases of both the transistors T₁ and T₂, emitter potential of transistors T₁ and T₂ becomes very low because of conductivity of transistor T₂ and diode D becomes to effect resistance to current, so that transistor T₁ is made nearly non-conductive and LED₁ does not emit any light. Thus, LED₂ emits light when down-beat signal K_n of level 0 is applied to driving circuit 5 and LED₁ emits light with other colour when down-beat signal K_n is made "1" level and tempo signal A of level "0" is applied to driving circuit 5, indicator 6 emitting on and off different colour lights successively at a single point to visually indicate tempo and rhythm.

FIG. 4 is a circuit diagram of another embodiment according to this invention, in which some reference numerals and marks refer as same as those in FIG. 1. NAND-gates G₁ and G₂ in FIG. 1 are respectively replaced by AND-gates G₆ and G₇. Reference numeral 4' designates a rhythm selecting switch, terminal ① of

which is connected to output Q of flip-flop F_1 and terminal ④ is connected to output Q of flip-flop F_3 while other terminals ② and ③ have the same connection as those of switch 4 in FIG. 1, terminal ① being free. The signal fed through switch 4' is applied to a differential circuit 10 to be detected its rising up. The output of differential circuit 10 is then applied to monostable-multivibrator 3 which generates a some length pulse of level "1" in response to the output of differential circuit 10. This output pulse from monostable-multivibrator is fed to a conventional down-beat sound generator (not shown), with tempo signals, to generate rhythm sounds, and is further fed to an inverter 11 where the output signal of level "1" is inverted to that of level "0" to reset flip-flops F_1 , F_2 and F_3 .

Thus, down-beat signal generating circuit 2' operates as a divided by n counter ($n=1, 2, 3, 4$ and 6), giving output of level "1" to the down-beat sound generator and output of level "0" (K_n) to an indicator driving circuit 5'.

Indicator driving circuit 5' includes three transistor T_3 , T_4 and T_5 . The emitters of transistors T_3 and T_4 are connected in common to the power source VC . The base of transistor T_3 is connected to the output of inverter 11 to receive down-beat signal K_n of level 0 while the base of transistor T_4 is connected with the collector of transistor T_3 by way of a resistor 12. The collectors of the transistors T_3 and T_4 are respectively connected to light emitting diodes LED_2 and LED_1 through resistor 13 and 14. The other terminals of the LED_1 and LED_2 are in common connected to the collector of transistor T_5 which emitter is connected to ground and which base is to receive inverted tempo signal through an inverter 15.

An inverted tempo signal of level 1 applied to the base of transistor 5 makes transistor 5 conductive allowing current to run through LED_1 and LED_2 . At the same time, when a down-beat signal K_n is applied to the base of transistor T_3 , transistor T_3 is made conductive to allow current to run through resistor 13 and LED_2 , which causes the potential on the base of transistor T_4 to rise up to high level so that transistor T_4 is made non-

conductive. Thus down-beat signal K_n makes LED_2 emit light for a down beat. In the absence of down-beat signal K_n , a tempo signal A makes LED_1 emit different colour light for up beat as transistor T_3 is non-conductive and lower potential is applied on the base of transistor T_4 to make it conductive.

It is to be understood that the invention is not limited in the above embodiments. Two different colour light LEDS may be energized at the same time for a down-beat, effecting a mixed colour display, and three different colour light LEDS may be used for down-beat, up-beat and medial-beat.

What I claim is:

1. An electronic metronome comprising a tempo signal generating means having an output, a down-beat signal generating means connected with said output of said tempo signal generating means, said down-beat signal generating means receiving a tempo signal from said tempo signal generating means and generating a down-beat signal therefrom, an indicator driving circuit connected to said tempo signal generating means and to said down-beat signal generating means and receiving signals therefrom, said indicator driving circuit having first and second outputs, a first LED and a second LED connected respectively to said first and second outputs of said indicator driving circuit, said indicator driving circuit energizing said first LED to make it conduct when said indicator driving circuit receives only said tempo signal and energizing said second LED to make it conduct when said indicator driving circuit receives both said tempo signal and said down-beat signal, said first LED being different from said second LED in colour and being packaged close to said second LED.

2. An electronic metronome according to claim 1, in which said first LED and second LED are packaged together in a single envelope.

3. An electronic metronome according to claim 1, in which said down-beat signal generating means comprises counting means for producing a signal every n tempo signals and selecting switch means for selecting the value of n .
